Fig-3

FIG. 1 is a perspective view of a mounting structure for photodetector heads for inspecting needles of circular knitting machines, embodying our new design;

FIG. 2 is a top plan view of the mounting structure;

FIG. 3 is a bottom view thereof;

FIG. 4 is a side elevation view of the mounting structure, viewed from the bottom of FIG. 2;

FIG. 5 is a front elevation view of the mounting structure, viewed from the right hand side of FIG. 2;

FIG. 6 is a side elevation view of the mounting structure, viewed from the opposite side of FIG. 4; and

FIG. 7 is a rear elevation view of the mounting structure, viewed from the top of FIG. 2.

We claim:

The ornamental design for an adjustable mounting structure for detector heads for inspecting needles of circular knitting machines, as shown and described.
